Preheater Corpora-

**Application July 30
3 Claims.**

The present invention relates to regenerative

The present invention relates to regenerative air preheaters and particularly to improved sealing means between the rotary and stationary parts thereof.

A regenerative air preheater has a rotor made up of a cylindrical shell joined to a rotor post by radial partitions which form compartments carrying heat transfer material that is alternately contacted by heating gas and air or other fluid to be heated as the rotor turns about its axis to dispose the plates in a stream of heating gas and then in a stream of air or other fluid. The rotor is enclosed within a housing which is provided opposite the ends of the rotor with sector plates formed with apertures for the passage of the fluids to and from the rotor. It is customary to mount circumferential sealing strips on the end edges of the shell to wipe against the end or sector plates so that the streams of gas and air are caused to pass through the rotor and prevented from by-passing the heat transfer material by flowing around the rotor in the narrow annular space that forms a clearance between the rotor shell and surrounding housing.

The invention contemplates an improved form of circumferential sealing means for regenerative preheaters or like apparatus and will be best understood upon consideration of the following detailed description of an illustrative embodiment of the invention when read in conjunction with the accompanying drawings in which:

Figure 1 is a sectional elevational view in diagrammatic form of a rotary regenerative air pre-heater embodying the present invention;

Figure 2 is a fragmentary sectional view on an enlarged scale showing the cooperative sealing means carried by the rotor shell and end plates of the housing in accordance with the present invention; and

Figure 3 is a fragmentary elevational view showing part of the sealing strip carried by the rotor shell.

The heat exchanger apparatus comprises a rotor mounted within a housing 10 to be driven at slow speed through its centrally located rotor post 11 by a motor and reduction gearing 12. The rotor consists of a cylindrical shell 13 interiorly divided into a plurality of wedge or sector-shaped compartments by radial partitions 14 of which one is shown in Figure 2, these partitions securing the shell to the rotor post. Circumferentially extending partitions or diaphragms 15 mounted concentrically with the rotor post 11 subdivide the sector-shaped compartments into a number of sections, each of which contains a

FLEXIBLE CIRCUMFERENTIAL SEAL FOR ROTARY HEAT EXCHANGERS

Opposite each end of the rotor a stationary sector plate 17 closing the end of housing 10 is provided with openings 18, 19 for the flow of gas and air. The air and gas openings 18, 19 in the sector plate are separated by imperforate por-

10 tions which are at least as wide as the maximum width of the sector-shaped compartments of the rotor so that radial seals 20 (Figure 2) on the partitions 14 by wiping against the imperforate parts of the sector plates 17 prevent cross flow 15 of air and gas between their respective passages.

Hot gases from a boiler or other source of

waste heat are admitted to the rotor from a duct 23 and passing over the heat transfer material 16 are discharged into a duct 24 leading to an induced draft fan, not shown. Air or other fluid to be heated is supplied under pressure by a forced draft fan, not shown, through a duct 25 to the air side of the preheater and after being heated by contact with the plates 16 is conveyed

25 through the duct 26 to the boiler furnace or other point of use. The construction described above is conventional.

To assure that the streams of gas and air pass over the heat transfer material 16 in the rotor 30 and to minimize leakage of gas and air, by-passing the rotor through the space 27 between the rotor shell 13 and housing 10 circumferential seals are customarily mounted on the end edges of the rotor shell 13 to contact the opposing faces 35 of the end or sector plates 17.

In accordance with the present invention the circumferential sealing means includes annular or ringlike members 30 approximating the rotor in diameter and mounted on the sector plates 17 opposite both ends of the rotor. Each annular seal 30 is formed with a U-shaped groove 31 facing and aligned with the adjacent end edge of the rotor shell 13. To cooperate with the channel-like seals 30 the rotor shell 13 carries sealing strips 32 projecting from the end edges of the rotor shell into the grooves 31 of the sealing members so that they may be maintained in contact with one of the sealing surfaces 33 or 34 of the latter by pressure differential across the seal strip. The part of a seal strip 31 traversing the gas passage with the rotor would be drawn by the suction of the induced draft fan to bear against the inner wear surface 34 of the seal while on the air side of the exchanger the seal strips would bear against the outer wear sur-

faces 33 of the rings 30, being forced against the latter by the positive air pressure produced by the forced draft fan. The seal strips 31 thus act as curtains alternately in contact with one or the other wear surfaces 33, 34 of the annular members 30 to positively close off the gas and air passages from the space 27 between the rotor shell 13 and the surrounding housing 10.

The seal strips 32 are of a pliable material such as glass fabric or other suitable material which is flexible enough to permit free movement across the space between the sealing surfaces 33 and 34. This space is wide enough to allow for any eccentricity of the rotor without causing undue rubbing of the seal strips. The seal strips 32 are preferably made in two layers *a* and *b* and the portions of each layer projecting from the edge of the rotor shell 13 are provided at intervals with slots 35 to improve the flexibility; these slots are staggered in the two layers as appears in Figure 3 to avoid leakage.

The wearing surfaces 33 and 34 on the annular channel members 30 are preferably of such material as will resist corrosion and wear. A heavy chromium plated surface on these seals is considered preferable. These rings are also preferably made in segments so that portions may readily be replaced when necessary.

What is claimed is.

1. In a regenerative air preheater or the like having passages for a heating gas and air or other gaseous fluid to be heated, a rotor made up of a cylindrical shell joined to a rotor post by radial partitions forming compartments that carry heat transfer material, and a housing surrounding the rotor and provided opposite the ends of the latter with sector plates formed with apertures for the flow of heating gases and air to and through the rotor under the action of induced and forced draft fans; annular channel shaped sealing members mounted on the inner faces of said sector plates opposite the rotor in alinement with the end edges of the cylindrical shell of the rotor; and flexible sealing strips mounted on the end edges of said rotor shell and projecting from the end edges of said shell into contact with one wall of said channel when traversing the gas passage and with the opposite wall of said channel when traversing the air passage when swung into contact therewith by the differential pressure existing across said strips.
2. In a regenerative air preheater or the like having passages for a heating gas and air or other gaseous fluid to be heated, a rotor made up

of a cylindrical shell joined to a rotor post by radial partitions forming compartments that carry heat transfer material, and a housing surrounding the rotor and provided opposite the ends of the latter with sector plates formed with apertures for the flow of heating gases and air to and through the rotor under the action of induced and forced draft fans; annular channel shaped sealing members mounted on the inner faces of said sector plates opposite the rotor and formed with generally U-shaped grooves facing and in alinement with the end edges of the cylindrical shell of the rotor; and sealing strips of pliable material adapted to flex when subjected to fluid pressure mounted on the end edges of said rotor shell and projecting from the end edges of said shell into the grooves of said annular channels for cooperation with one wall of said groove when traversing the gas passage and with the opposite wall of said groove when traversing the air passage and brought into contact therewith by the differential pressure existing across said strips.

3. In a regenerative air preheater or the like having passages for a heating gas and air or other gaseous fluid to be heated, a rotor made up of a cylindrical shell joined to a rotor post by radial partitions forming compartments that carry heat transfer material, and a housing surrounding the rotor and provided opposite the ends of the latter with sector plates formed with apertures for the flow of heating gases and air to and through the rotor under the action of induced and forced draft fans; annular sealing members of a diameter approximating that of the rotor mounted on the housing in positions confronting the end edges of the rotor shell; and flexible sealing strips carried by the ends of the rotor and maintained in contact with said annular sealing members by the pressure differential produced across said sealing strips by said fans.
